BASIC DERIVATIVES OF SUBSTITUTED
CYCLOALKANE CARBOXYLIC ACIDS
AND METHODS OF PREPARING SAMEWilliam A. Lott, Maplewood, and John Krapcho,

poration of VirginiaNo Drawing. Application February 12, 1952,
Serial No. 271,272

13 Claims. (Cl. 260—294)

1

This application is a continuation-in-part of our application Serial No. 218,516, filed March 30, 1951; and now abandoned.

This invention relates to, and has for its object, the provision of: (A) bases of the general formula

wherein $R-CO-$ is the acyl residue of a carboxylic acid,

represents an amino group, n represents one of the whole numbers 2 to 5 inclusive, and X is a member of the class consisting of O, NH, N(alkyl), and N(aryl) groups; (B) acid-addition salts of (A); (C) quaternary ammonium salts of (A); and (D) methods of preparing (A), (B) and (C). [In the acyl residue $R-CO-$, the radical R may, for example, be an aliphatic, aromatic, alicyclic, or heterocyclic group; and it may be unsubstituted or may contain substituents such as alkyl, alkoxy, hydroxy and halogen groups.]

Among the preferred compounds of this invention are: basic esters having the following general formula

wherein

represents a member of the class consisting of

1-piperidyl, 1-pyrrolidyl and 4-morpholinyl, and n has the meaning given hereinbefore; the acid-addition salts thereof; and the quaternary ammonium salts thereof with alkyl halides.

These compounds are useful and advantageous therapeutic agents, especially antispasmodics. Thus, the hydrochloride of 2-diethylaminoethyl 1-benzoylecyclopropanecarboxylate, a compound representative of group B defined hereinbefore,

2

may be administered in the same general manner (e. g. orally, in tablet form) for the same general purpose (e. g. for reduction of rigidity in Parkinson's disease) and with the same general results as the hydrochloride of β -diethylaminoethyl 1-phenylcyclopentanecarboxylate, an antispasmodic widely used and accepted by the medical profession. Additionally, these compounds (especially the quaternary ammonium salts, such as the methobromide of 2-diethylaminoethyl 1-benzoylecyclopropanecarboxylate) exhibit anti-secretory effects, and hence are useful in the treatment of gastric ulcers, for example.

Basic esters of the general formula:

wherein r is one of the whole numbers 2 and 3, are prepared by the method which essentially comprises interacting the corresponding acid (I), which may be in salt, (especially alkali-metal salt) form, with a basic aliphatic halide (II) of the general formula:

in an organic solvent for the reactants, removing the solvent and recovering the residue. The reaction occurs in the presence or absence of an alkaline condensing agent. Thus the following acids I and basic aliphatic halides II, inter alia, may be used for the preparation of the basic esters of this invention.

I

- 40 1-benzoylecyclopropanecarboxylic acid
- 41 1-benzoylecyclobutanecarboxylic acid
- 42 1-sorboylecyclopropanecarboxylic acid
- 43 1-nicotinoylcyclopropanecarboxylic acid
- 44 1-cinnamoylcyclopropanecarboxylic acid
- 45 1-(2-furoyl)-cyclopropanecarboxylic acid
- 46 1-hexahydrobenzoylecyclopropanecarboxylic acid
- 47 1-(α -naphthoyl)-cyclopropanecarboxylic acid
- 48 1-(2-thenoyl)-cyclopropanecarboxylic acid
- 49 1-(2-thenoyl)-cyclobutanecarboxylic acid
- 50 1-(2-methylpropanoyl)-cyclopropanecarboxylic acid
- 51 1-anisoylcyclopropanecarboxylic acid
- 52 1-anisoylcyclobutanecarboxylic acid
- 53 1-propenoylcyclopropanecarboxylic acid
- 54 1-acetylcylopropanecarboxylic acid

- 2-diethylaminoethyl chloride
3-diethylaminopropyl chloride
3-(1-piperidyl)-propyl chloride
2-(1-pyrrolidyl)-ethyl chloride
2-(4-morpholinyl)-ethyl chloride
3-diethylamino-2,2-dimethylpropyl chloride
2-(1-piperidyl)-ethyl chloride
2-diethylamino-1-ethyl-ethyl chloride
2-diethylaminoisopropyl chloride

[The acid reactants I are described in the literature, or are prepared as described hereinafter from compounds described in copending application Serial No. 271,273 filed of even date.]

While basic esters in which the cycloalkyl group is cyclopentyl or cyclohexyl can be prepared by the method described hereinbefore, they are preferably prepared by the method described hereinafter. The method essentially comprises interacting a base (III) of the general formula:

wherein s is one of the whole numbers 4 to 5 inclusive, with an acyl halide (IV) of the general formula $\text{R}'\text{CO}-\text{Halogen}$ in the presence of an alkaline condensing agent and in an inert organic solvent for the reactants.

Thus the following bases III and acyl halides IV, inter alia, may be used in the practice of this invention:

III

- 3-dimethylaminopropyl cyclohexanecarboxylate
2-(1-piperidyl)-ethyl cyclohexanecarboxylate
2-(4-morpholinyl)-ethyl cyclohexanecarboxylate
2-diethylamino-1-ethyl-ethyl cyclohexane-carboxylate
2-diethylaminoethyl cyclopentanecarboxylate
2-diethylaminoethyl cyclohexanecarboxylate
2-(1-piperidyl)-isopropyl cyclopentanecarboxylate
2-diethylaminoisopropyl cyclohexanecarboxylate
2-(1-pyrrolidyl)-ethyl cyclohexanecarboxylate
3-diethylamino-2,2-dimethylpropyl cyclohexanecarboxylate

[These basic esters may be obtained conveniently by reacting the appropriate cycloalkane carbonyl halide with the appropriate amino-aliphatic-alcohol (cf., Example 9 hereinafter).]

IV

- Sorboyl chloride
Cinnamoyl chloride
Nicotinoyl chloride
Benzoyl bromide
 α -Naphthoyl chloride
 β -Naphthoyl chloride
Anisoyl chloride
Propenoyl chloride
2-thenoyl chloride
2-methylpropanoyl bromide
Hexahydrobenzoyl chloride
Furoyl chloride

The alkaline condensing agents utilizable for the purposes of this invention comprise, inter alia, sodamide, lithium amide, sodium ethoxide, potassium t-butoxide, (metallic) alkali metals, such as sodium and potassium, (solid) alkali metal hydroxides, such as NaOH and KOH, and (preferably) alkali metal derivatives of tri-phenylmethane. Preferably the alkaline condensing agent is dissolved or suspended in an

inert organic solvent (especially ether) and this solution (or suspension) is used as the reaction medium.

The basic amides of this invention are obtained by interacting an ester (V) of the general formula:

wherein R' and n have the meaning given hereinbefore with an alkylene diamine (VI) having a free amino hydrogen. Thus the following reactants V and VI are utilizable in the practice of this invention.

V

- Ethyl 1-benzoylcyclopropanecarboxylate
Methyl 1-benzoylcyclobutanecarboxylate
Ethyl 1-benzoylcyclopentanecarboxylate
Ethyl 1-benzoylcyclohexanecarboxylate
Ethyl 1-(2-thenoyl)-cyclopropanecarboxylate
Ethyl 1-acetyl-cyclopropanecarboxylate
Ethyl 1-furoyl-cyclopropanecarboxylate

[These esters may be obtained conveniently by reacting an ester of the appropriate cycloalkane-carboxylic acid with the appropriate acyl halide IV, or by the method described in copending application Serial No. 271,273 filed of even date.]

VI

- N,N-dimethyl-N'-ethyl-ethylenediamine
N,N-diethyl-N'-methyl-ethylenediamine
N,N-diethyl-butylenediamine
N,N-diethyl-pentylenediamine
N,N-dimethyl-N'-phenyl-ethylenediamine
[JACS 68, 1999 (1946)]
N,N-diethyl-ethylenediamine
N-(2-amino-ethyl)-piperidine
N-(2-amino-ethyl)-pyrrolidine
N,N-dimethyl-propylenediamine
N-(2-amino-ethyl)-morpholine
N,N-diethyl-isopropylenediamine

In these methods, the bases may be obtained as such (i. e., as the free base) or in the form of their acid-addition salts (e. g., as hydrochlorides, if the halogen in the reactant is chlorine). The acid-addition salts may be converted to the free bases in the conventional manner, i. e., by neutralization with alkali; and the free bases may be converted to other acid-addition salts by reacting the base with the desired acid in a suitable solvent. The utilizable acids comprise, inter alia: hydrobromic, boric, nitric, lactic, tartaric, citric, succinic, phosphoric, sulfuric, maleic, fumaric and (especially) hydrochloric.

By the addition of alkyl halides, dialkyl sulfates, aralkyl halides, aryl halides, or the like, there are obtained in the usual manner quaternary ammonium salts of the basic esters and amides (A) described hereinbefore.

The following examples are illustrative of the invention.

EXAMPLE 1

65 Preparation of 2-diethylaminoethyl 1-benzoylcyclopropanecarboxylate hydrochloride

A mixture of 31.5 g. 1-benzoylcyclopropane-carboxylic acid [J. Chem. Soc., 47, 836 (1885)], 22.5 g. 2-diethylaminoethyl chloride and 300 ml. dry isopropyl alcohol are refluxed for seven hours. The small quantity of insoluble material in the reaction mixture is filtered off, and the filtrate diluted with 500 ml. dry ether to yield about 39.0 g. of a colorless crystalline product which melts

at about 132-133° C. After recrystallization from butanone, the product melts at about 133-134° C.

EXAMPLE 2

Preparation of 2-(1-piperidyl)-ethyl 1-benzoylcyclopropanecarboxylate, and the hydrochloride thereof

A suspension of sodium isopropoxide, prepared from 8.3 g. sodium and 300 ml. isopropyl alcohol, is cooled and treated with 34.2 g. 1-benzoylcyclopropanecarboxylic acid, followed by the addition of 33.1 g. 2-(1-piperidyl)-ethyl chloride hydrochloride. The resulting mixture is stirred and refluxed for 22 hours, the solvent is removed by distillation under reduced pressure, and the residue is treated with 50 ml. water. The mixture is then extracted with 400 ml. ether and the extract dried over magnesium sulfate. After evaporation of the solvent, the residue is fractionated to yield about 45.5 g. of the base, a colorless oil which distills at about 161-168° C. at 0.2 mm. Part of this material (23.1 g.) is dissolved in 300 ml. dry ether and the solution is treated with a slight excess of ethereal hydrogen chloride, to yield a colorless precipitate (the hydrochloride of the base) weighing about 25.1 g., and melting at about 135-136° C. After two crystallizations from butanone, the crystalline product melts at about 137-138° C.

EXAMPLE 3

Preparation of 2-dimethylaminoethyl 1-benzoylcyclopropanecarboxylate, and the hydrochloride thereof

A solution of 4.23 g. sodium in 350 ml. isopropyl alcohol is treated with 35.0 g. 1-benzoylcyclopropanecarboxylic acid, followed by addition of a solution of about 24.0 g. 2-dimethylaminoethyl chloride in 150 ml. of toluene. This mixture is refluxed for two hours and the product, the free base, is isolated in the manner described in Example 2; yield about 32.6 g.; B. P. about 133-136° C./0.5 mm. Part of this base (21.5 g.) is dissolved in 50 ml. of absolute alcohol and treated with one equivalent of alcoholic hydrogen chloride. Dilution of this solution with ether yields a colorless precipitate, the hydrochloride, weighing about 24.0 g. M. P. about 131-133° C. After crystallization from isopropyl alcohol, the crystalline product melts at about 134-135° C.

EXAMPLE 4

Preparation of 2-dipropylaminoethyl 1-benzoylcyclopropanecarboxylate, and the hydrochloride thereof

A solution of 2.88 g. sodium in 400 ml. isopropyl alcohol is treated with 23.8 g. 1-benzoylcyclopropanecarboxylic acid, followed by addition of 20.4 g. 2-dipropylaminoethyl chloride. The mixture is refluxed for two hours and the product, the free base, is isolated in the manner described in Example 2; yield about 26.5 g.; B. P. about 136° C./0.2 mm. Part of this base (17.0 g.) is dissolved in 300 ml. of ether and then treated with a slight excess of ethereal hydrogen chloride. The resulting precipitate, the hydrochloride, weighing about 18.5 g., M. P. about 88-92° C., is recrystallized several times from a mixture of butanone and diethyl ether, M. P. about 93-94° C.

EXAMPLE 5

Preparation of 2-(4-morpholinyl)ethyl 1-benzoylcyclopropanecarboxylate, and the hydrochloride thereof

A solution of 4.56 g. of sodium in 350 ml. iso-

propyl alcohol is treated with 37.7 g. 1-benzoylcyclopropanecarboxylic acid, followed by addition of 31.5 g. 2-(4-morpholinyl)ethyl chloride. This mixture is refluxed for three hours and the product, the free base, is isolated in the manner described in Example 2; yield about 50.0 g.; B. P. about 167-169° C./0.2 mm. Part of this base (30.8 g.) is dissolved in 100 ml. of absolute alcohol and treated with one equivalent of alcoholic hydrogen chloride. Dilution of this solution with ether yields a crystalline precipitate, the hydrochloride, weighing about 34.0 g., M. P. about 143-144° C. The product crystallizes from isopropyl alcohol, M. P. about 143-144° C.

EXAMPLE 6

Preparation of 3-dimethylaminopropyl 1-benzoylcyclopropanecarboxylate, and the hydrochloride thereof

A solution of sodium isopropylate, prepared from 4.23 g. of sodium and 350 ml. isopropyl alcohol, is treated with 35.0 g. 1-benzoylcyclopropanecarboxylic acid, followed by addition of 22.4 g. 3-dimethylaminopropyl chloride. The mixture is refluxed for two hours and the product, the free base, is isolated in the manner described in Example 2; yield about 38.6 g., B. P. about 135-138° C./0.3 mm. Part of this base (25.5 g.) is dissolved in 50 ml. absolute alcohol and treated with one equivalent of alcoholic hydrogen chloride. Dilution of this solution with ether yields a crystalline product, the hydrochloride, weighing about 26.5 g., M. P. about 144-146° C. After recrystallization from isopropyl alcohol, the crystalline material melts at about 145-146° C.

EXAMPLE 7

Preparation of 2-diethylaminoethyl 1-(2-thienoyl)-cyclopropanecarboxylate, and the hydrochloride thereof

(a) To a cooled solution of sodium ethoxide prepared from 6.7 g. of sodium and 100 ml. absolute ethanol, is added dropwise a mixture of 57.0 g. ethyl 2-thienoyl-acetate [J. Amer. Chem. Soc., 66, 1768 (1944)] and 54.5 g. ethylene bromide; and the mixture is refluxed for six hours. After cooling, the mixture is treated with a solution of 5.0 g. sodium in 100 ml. ethanol and the material is then refluxed for five hours, cooled and diluted with 500 ml. water. The resulting solution is extracted with ether and the ethereal phase washed several times with water until the aqueous phase is neutral. The ether phase is dried over magnesium sulfate, filtered and solvent evaporated. Distillation of the residue yields about 23.8 g. of the ester, ethyl 1-(2-thienoyl)-cyclopropane carboxylate; B. P. about 127-130° C./4 mm.; $n_{D}^{23}=1.5434$.

(b) Part of the above ester (22.9 g.) is added to a solution of 23 g. of potassium hydroxide in 300 ml. of 95% alcohol and the resulting solution refluxed for two hours. After cooling, the mixture is diluted with 500 ml. of water and then extracted several times with ether. The aqueous phase is acidified with dilute sulfuric acid and the resulting liberated acid extracted with ether. After drying over magnesium sulfate, the solvent is evaporated and the residue crystallized as long blade-like crystals. This material is suspended in hexane and filtered; yield about 12 g., M. P. about 135-138° C. After crystallization from 50% alcohol, the 1-(2-thienoyl)cyclopropanecarboxylic acid weighs about 9.5 g., M. P. about 139-141° C. (with evolution of a gas).

(c) A solution of 0.94 g. sodium in 150 ml. iso-

propyl alcohol is treated with 8.0 g. 1-(2-thenoyl)-cyclopropanecarboxylic acid, followed by the addition of 6.8 g. 2-diethylaminoethyl chloride. The mixture is refluxed for three hours and the product, the free base, is isolated in the manner described in Example 2; yield about 9.6 g., B. P. about 146-148° C./0.5 mm. This material is dissolved in 50 ml. absolute alcohol and treated with one equivalent of alcoholic hydrogen chloride. Dilution of this solution with ether produces a crystalline product weighing about 10.8 g., M. P. about 136-137° C. After crystallization from butanone, this hydrochloride melts at 137-138° C.

EXAMPLE 8

Preparation of 2-diethylaminoethyl 1-benzoylcyclobutanecarboxylate and the hydrochloride thereof

(a) *1-benzoylcyclobutanecarboxylic acid*.—A solution of 12.36 g. 1-(α -hydroxybenzyl)cyclobutanecarboxylic acid, prepared for example as described in my copending application Serial No. 271,273 filed of even date, in 60 ml. 1 N sodium hydroxide is diluted with 100 ml. water and then treated dropwise over a period of one hour with a solution of 6.32 g. potassium permanganate in 300 ml. water. After stirring for an additional two hours at room temperature, the purple-colored mixture is slowly warmed to 70° C. at which point it becomes colorless. The material is cooled, treated with charcoal, filtered, and the filtrate acidified with dilute sulfuric acid. The colorless crystalline product which separates is filtered and washed with water. This acid is dissolved in a small quantity of ether and precipitated by the addition of hexane to yield about 6.2 g. of product melting at 98° C. (with evolution of a gas). After crystallization from a mixture of benzene and hexane, the crystalline acid melts at about 103° C. (with evolution of a gas).

(b) 5.7 g. 1-benzoylcyclobutanecarboxylic acid, prepared in (a) above, is added to a cool solution of 0.65 g. sodium in 150 ml. isopropyl alcohol and the resulting slurry is then treated with 3.9 g. 2-diethylaminoethyl chloride. This mixture is refluxed for four hours, cooled and the solvent removed by distillation under reduced pressure. The residue is treated with 25 ml. water, the product extracted with ether and the resulting ethereal solution dried over magnesium sulfate. After evaporation of the solvent, the residue is fractionated to yield about 5.2 g. of the free base, B. P. about 148-151° C./0.3 mm. One gram of the distillate is dissolved in 20 ml. ether and treated with a slight excess of ethereal hydrogen chloride to yield a colorless precipitate, the hydrochloride which when purified by crystallization from butanone melts at about 135-136° C.

EXAMPLE 9

Preparation of 2-diethylaminoethyl 1-benzoylcyclopentanecarboxylate and the hydrochloride thereof

(a) *2-diethylaminoethyl cyclopentanecarboxylate*.—A cooled solution of 38.5 g. of cyclopentanecarbonyl chloride [Perkin, J. Chem. Soc. 65, 99 (1884)] in 150 ml. dry benzene is treated dropwise (30 minutes) with a solution of 34.0 g. 2-diethylaminoethanol in 100 ml. of dry benzene; a colorless precipitate separating. After stirring for 1 hour at room temperature, the mixture is refluxed for 2 hours, cooled, and extracted with 250 ml. of water. The aqueous phase is then washed with 100 ml. ether and treated with a

cooled solution of 16.0 g. of sodium hydroxide in 80 ml. water; and the liberated base is extracted with 300 ml. ether and dried over magnesium sulfate. After evaporation of the ether, the residue is fractionated to yield about 44 g. of colorless product, boiling at about 96-98° C./2 mm.

(b) 19.4 g. 2-diethylaminoethyl cyclopentanecarboxylate is added to 650 ml. of 0.14 M. ethereal solution of triphenylmethylsodium [J. A. C. S. 63, 3156 (41)], the mixture is stirred for 2 hours at room temperature, and 13.0 g. benzoyl chloride is added over a period of 15 minutes. After allowing the mixture to stand overnight, it is refluxed for 2 hours, cooled, and 100 ml. water is added. The aqueous layer is discarded, and the ether layer is extracted first with 8.5 ml. concentrated hydrochloric acid in 100 ml. water and then with 50 ml. water. These aqueous extracts are combined, made alkaline with a solution of 5.0 g. sodium hydroxide in 25 ml. water, and extracted with 300 ml. ether to yield the free base. The latter is dried over magnesium sulfate and the solvent is evaporated; and the residue is dissolved in 400 ml. dry ether and treated with a slight excess of ethereal hydrogen chloride, to yield about 32 g. of a colorless precipitate (the hydrochloride of the free base), melting at about 121-123° C. After 2 crystallizations from butanone, the product melts at about 127-128° C.

EXAMPLE 10

Preparation of 2-diethylaminoethyl 1-benzoylcyclohexanecarboxylate and the hydrochloride thereof

650 ml. of a 0.14 M. ethereal solution of triphenylmethylsodium is treated with 20.5 g. 2-diethylaminoethyl cyclohexanecarboxylate [B. P. 98-100° C. at 2 mm., prepared from the hydrochloride described in Chem. Abstracts 43, 1023 (1949)] and then with 12.6 g. benzoyl chloride, as described in Example 9b, yielding a crude residue (the base) weighing about 32 g.

18 g. of this crude residue is dissolved in 300 ml. ether and treated with a slight excess of ethereal hydrogen chloride, yielding about 18.5 g. of precipitate (the hydrochloride of the base), melting at about 130-135° C. After 2 crystallizations from butanone, the product melts at about 140-141° C.

EXAMPLE 11

Preparation of 2-diethylaminoisopropyl 1-benzoylcyclohexanecarboxylate hydrochloride

(a) *2-diethylaminoisopropyl cyclohexanecarboxylate*.—A solution of 60.0 g. cyclohexanecarbonyl chloride [Ber. 30, 1941 (1897)] in 200 ml. dry benzene is treated with a solution of 53.6 g. 2-diethylaminoisopropanol in 150 ml. dry benzene, as described in Example 9a, yielding about 89.5 g. of the basic ester, distilling at about 100-101° C. (2 mm.).

(b) Interaction (as described in Example 9b) of 650 ml. of a 0.14 M. ethereal solution of triphenylmethylsodium with 22 g. 2-diethylaminoisopropyl cyclohexanecarboxylate, prepared as described in (a), above, followed by 13.0 g. benzoyl chloride, yields about 32.2 g. 2-diethylaminoisopropyl 1-benzoylcyclohexanecarboxylate hydrochloride. This crude product melts at about 137-139° C.; and after recrystallization from 150 ml. butanone, it melts at about 144-145° C.

11

3. A quaternary ammonium salt of a base of the general formula:

4. An acid-addition salt of a base of the general formula:

5. A quaternary ammonium salt of a base of the general formula:

6. 2-diethylaminoethyl 1-benzoylcyclopropane-carboxylate hydrochloride.

7. 2-dimethylaminoethyl 1-benzoylcyclopropanecarboxylate hydrochloride.

8. 2-diethylaminoethyl 1-(2-thenoyl)-cyclopropanecarboxylate hydrochloride.

9. The methobromide of 2-diethylaminoethyl 1-benzoylcyclopropanecarboxylate.

10. The methobromide of 3-dimethylaminoethyl 1-benzoylcyclopropanecarboxylate.

11. A base of the general formula:

12. A base of the general formula:

40

12

13. The method which essentially comprises interacting

wherein R is a member of the class consisting of phenyl and thienyl groups, with a basic aliphatic halide of the general formula

10

wherein

15

represents a member of the class consisting of

20

1-piperidyl, 1-pyrrolidyl, and 4-morpholinyl groups, in an organic solvent for the reactants, removing the solvent and recovering the residue.
